UNITED STATES PATENT OFFICE.

EDWIN H. STEEDMAN, OF ST. LOUIS, MISSOURI, ASSIGNOR TO CURTIS & CO. MFG. CO.,
OF WELLSTON, MISSOURI, A CORPORATION OF MISSOURI.

DESIGN FOR AN AIR-COMPRESSOR CASING.

60,066.

Specification for Design.

Patented Dec. 20, 1921.

Application filed December 27, 1920. Serial No. 433,511. Term of patent 14 years.

To all whom it may concern:

Be it known that I, EDWIN H. STEEDMAN, a citizen of the United States, residing at St. Louis, Missouri, have invented a certain new, original, and ornamental Design for an Air-Compressor Casing, of which the following is a specification, reference being had to the accompanying drawing, forming part thereof.

The figure of the drawing is a perspective

view of my new design for an air compressor casing.

I claim:

The ornamental design for an air compressor casing, as shown.

EDWIN H. STEEDMAN.
